[57] CLAIM

The ornamental design for a circuit card support, substantially as shown and described.

DESCRIPTION

FIG. 1 is a perspective view from the front and one side showing a new design;

FIG. 2 is an opposite side elevational view thereof on an enlarged scale;

FIG. 3 is a front elevational view thereof on an enlarged scale;

FIG. 4 is a rear elevational view thereof on an enlarged scale;

FIG. 5 is a top plan view thereof on an enlarged scale; and

FIG. 6 is a bottom plan view thereof on an enlarged scale;

FIG. 7 is a fragmentary perspective view from the back and side shown in FIG. 2.

The interior card guide structure is partially shown in FIGS. 3, 4 and 7 for convenience of illustration. The slots in the top of the support are partially shown in FIG. 7 for convenience of illustration.

FIG. 4

FIG. 1

FIG. 2

FIG. 5

FIG. 3

FIG. 6

FIG. 7
